UNITED STATES PATENT OFFICE

2,678,123

TYPEWRITER FRAME STRUCTURE

Raymond L. Smith, Arlington, Va.

Application February 29, 1952, Serial No. 274,113

1 Claim. (Cl. 197—186)

2

The present invention relates to a typewriter frame structure and it consists in the combinations, constructions and arrangements of parts herein described and claimed.

The present invention is a continuation in part of the invention disclosed in my prior application Serial No. 85,768, filed April 6, 1949, and since issued as Patent No. 2,587,778, dated March 4, 1952 and in my prior application Serial No. 223,973, filed May 1, 1951 and since issued as Patent No. 2,591,310, dated April 1, 1952, the latter forming a continuation in part of the aforesaid application, Serial No. 85,768. In the prior applications, it will be noted that the first and second rows of keys are each provided with key levers having U-shaped key clearance portions and it has been found that when a typewriter so equipped is mounted upon a conventional typewriter pad that the U-shaped key clearance portions sometimes come into contact with the upper face of such pad. Accordingly, it is a prime object of the present invention to provide a guard member which may be quickly and easily attached to the frame of a typewriter of the character above set forth and which guard member will assure clearance for the aforesaid U-shaped key clearance portions at all times and particularly when a typewriter pad or cushion is utilized with a typewriter of this character.

Another object of the invention is to provide a device of the character set forth which is simple in construction, inexpensive to manufacture and yet effective and efficient in use.

A further object of the invention is to provide, in a device of the character set forth, means whereby pencils and like objects are automatically prevented from becoming positioned atop said guard.

Another object of the invention is to provide a novel guard member having means for the prevention of interference with the key levers of a typewriter by the conventional typewriter pad.

Other and further objects of the invention will become apparent from a reading of the following specification taken in conjunction with the drawing, in which:

Figure 1 is a vertical sectional view of an embodiment of the invention shown mounted upon a typewriter of the character above set forth and showing such typewriter in position upon a flat supporting surface.

Figure 2 is a view similar to Figure 1 but showing the typewriter with a supporting pad positioned between the same and its supporting flat surface,

Figure 3 is a fragmentary sectional view, partly broken away, taken along line 3—3 of Figure 1,

Figure 4 is a fragmentary perspective view of a device embodying the present invention, and

Figure 5 is a fragmentary sectional view similar to Figure 2 but showing a modified form the invention may assume.

Referring more particularly to the drawing, there is shown therein a typewriter frame 10 provided with dependent supporting feet 11 having undercoverings of yieldable material, as indicated at 12, such structure being conventional.

The typewriter is shown as having four rows of keys, namely a first row generally indicated at 13, a second row generally indicated at 14, a third row generally indicated at 15 and a fourth row generally indicated at 16.

The keys in the first and second rows 13 and 14 of the keys in the typewriter are provided with key levers having U-shaped key clearance portions 17 and it will be apparent that when any key in the first row 13 or second row 14 of such keys is depressed in conventional manner that the bottom of its associated U-shaped key clearance portion 17 will reach a point in close proximity to, for example, a flat supporting surface 18. In Figure 2 there is shown interposed between the surface 18 and the typewriter a conventional pad 19 of yieldable material such as rubber or the like which is conventional in character. The present invention is particularly designed to guard against interference with the U-shaped portion 17 by the upper surface of such pad 19.

Accordingly, there is provided a guard member 20 which is generally indicated at 20 and which is provided with an elongated transversely extending bight portion 21 and bifurcated end portions 22 each having a notch 23 therein. The frame 10 has integrally formed upon the inner face of each side thereof a screw-receiving collar 25 for the reception therein of a headed screw 26.

The upper or top face of the bight portion 21 of the guard 20 is provided with a convex forward portion 27 from which extends a generally downwardly and rearwardly extending portion 28, as clearly seen in Figures 1, 2 and 4 and it will be apparent that there is on the outer face of each bifurcated end portion a recess 24 which provides a shoulder 29 in each of the end portions 22.

In that form of the invention illustrated in Figure 5 the upper or top face 30 of the bight portion 21 is flat in nature and extends downwardly and rearwardly. In both forms of the invention the bight portion 21 of the guard 20 is so designed that when the guard is in position

upon the typewriter and the typewriter is placed upon the supporting surface 18, there will be a slight clearance 32 between its bottom face 31 and the surface 18 even taking into consideration the compressed condition of the members 12 at such time.

In operation, it will be apparent that the guard 20, in both forms of the invention, may be quickly and easily attached to the frame 10 by mounting the bifurcated portions 22 over the screw receiving collars 25 and thereafter threading the screws 26 inwardly until the heads thereof rigidly secure the guard 20 to the frame 10. When this is accomplished, it will be apparent that the lower edges of the frame 10 will abut against the shoulders 29 of the guard 20 thus assuring an exact clearance between the face 31 and a supporting surface 18. The keys in both of the rows 13 and 14 of the typewriter may then be depressed in conventional manner and it will be apparent that the lowermost portions of the U-shaped key clearance portions of the key levers, indicated at 33, will now reach a point immediately above the upper surface of the guard member, thus protecting the key levers and particularly such lowermost points 33 from interference from any obstructions which may lie beneath the typewriter frame. In Figure 2, as aforesaid, the typewriter is shown mounted upon a conventional yieldable pad 19. It is in this condition that the guard member 20 is most effective since it will be apparent that the conventional feet 11 of the typewriter will sink into the pad 19 thus normally allowing the remainder of the pad which lies beneath the portion 17 to interfere with the proper use of the keys in rows 13 and 14. In such case, however, with the guard 20 in position upon the frame 10, such interference becomes impossible since the guard

member itself will depress that portion of the pad 19 lying thereunder.

In both forms of the invention it will be apparent that such articles as pencils and the like are prevented from accidentally positioning themselves atop the bight portion 21 of the guard 20 due to the fact that the upper faces thereof present no surface upon which such an article may rest. This structure also assures against obstructions lying below the critical portions 33 of the first and second rows of keys.

While but two forms of the invention have been shown and described herein, it will be readily apparent to those skilled in the art that many minor modifications may be made without departing from the spirit of the invention or the scope of the appended claim.

What is claimed is:

In combination, a typewriter having a frame, keys and key levers for said keys, a guard member extending transversely between the sides of the typewriter frame and beneath the lowermost portions of the key levers, said guard member having a bight portion and turned up bifurcated end portions, each of said end portions being recessed on its outer face and providing a shoulder engageable with the under edge of a side of the frame, and a fastening element for releasably securing each bifurcated end portion of the guard member to a side of the frame, said bight portion having a bottom face engageable with the typewriter pad upon the typewriter being supported thereon.
